UNITED STATES PATENT OFFICE.

MAX TORNOW, OF NEW YORK, N. Y.

REEFING SAILS.

No. 834,692.

Specification of Letters Patent.

Patented Oct. 30, 1906.

Application filed September 7, 1905. Serial No. 277,380.

To all whom it may concern:

Be it known that I, MAX TORNOW, a subject of the German Emperor, and a resident of the borough of the Bronx, city, county, and State of New York, have invented a certain new and useful Improvement in Reefing Sails, of which the following is a description.

The object I have in view is the production of a device for reefing sails which may be attached to existing vessels, which will comprise few and simple parts, will be easily applied, easily manipulated, not liable to get out of order, and which can be relied upon to be effective at all times.

Other objects will more fully appear from the disclosure contained in the following description and accompanying drawings.

I attain the objects of my invention by the apparatus illustrated in the accompanying drawings, which illustrate one embodiment, and in which—

Figure 1 is a view in perspective of a portion of a vessel and sail, showing the apparatus in position. Fig. 2 is a top view, partially in section, of the rolling device. Fig. 3 is a sectional view thereof taken on the lines 3 3 of Fig. 2 and looking in the direction of the arrow. Fig. 4 is a sectional view taken through the boom and sail and showing the boom-traveler; and Fig. 5 is a view of the end of the boom, partly in section, showing the boom-swivel.

In all of the views like parts are designated by the same reference characters.

In carrying out my invention I provide means for so mounting the boom that it may be rotated and the foot of the sail wound up upon it in a manner analogous to the action of a shade roller and curtain. The sail may be wound up by the rotation of the boom to any desired extent, and therefore reef bands or knittles will not be required, and the area of sail may be reduced to any desired extent.

In the drawings, 1 represents the boom, 2 the sail, and 3 the mast. The boom may be made with or without taper, as desired, it being found in practice that a tapered boom will permit the sail to roll sufficiently smooth upon it. Preferably the upper side of the boom is provided with a groove sufficiently large to contain the bolt-rope 4 on the foot of the sail. The sail may then be secured to the boom by any suitable means, such as a lacing

5, passing through eyelets formed in the sail above the bolt-rope (see Fig. 1) and holding 55 the foot of the sail smoothly upon the boom with the bolt-rope within the groove.

The boom is secured to the mast by the rolling device 6. This device comprises the boom-fitting 7, adapted to be attached to the 60 forward end of the boom and be supported upon the jaw portion 8 in such a manner that it may be rotated. The boom-fitting is provided with a socket, preferably arranged in the form of four wings 9. The four wings are 65 preferred to three or less, as they may be more readily bent in attaching the fittings to existing booms. The wings 9 are provided with holes 10, which are preferably countersunk for the passage of screws or bolts for attachment to the boom. The boom-fitting is also provided with a rectangular block 11, (see Fig. 3 and in dotted lines, Fig. 2,) adapted to enter a notch cut in the forward end of the boom. By employing the block 11 engaging 75 with the notch the torsional strain upon the fitting will be communicated to the boom without straining the screws. The office of the screws will be, therefore, mainly to resist strains in a longitudinal direction. 80

The boom-fitting is provided with an extension or stem 12, which enters a circular bearing formed in the jaw portion 8. The end of the stem is headed or riveted to form a flange 13, so as to hold the parts together 85 and yet permit the ready turning of the boom-fitting upon the jaw portion. The boom-fitting is also provided with a ratchet-wheel 14, by means of which it may be rotated. It is also provided with a lever 15, 90 having a bifurcated extremity which straddles the ratchet-wheel, and is journaled upon the extension 12 so that it may be readily rotated. This arm 15 carries a pawl 16, provided with an adjusting-handle 17 adjacent 95 to the operating-handle 15. A pawl 18 is suitably mounted upon an extension formed upon the side of the jaw portion 8 and is so arranged as to engage with the ratchet-wheel 14. If necessary, springs are provided to insure the engagement of the pawls with the ratchet; but if formed as illustrated the pawls will rest within the notches of the ratchet. 100

The jaw portion 8 is provided with a roller 105 19, supported upon a bolt 20 or other suitable

shaft and so arranged as to engage with the mast. This roller permits the ready up-and-down movement of the jaw portion upon the mast irrespective of the torsional strain 5 upon it.

The boom-traveler 21 is adapted to support one of the sheet-blocks 22 intermediate the ends of the boom. It is formed of a single annular piece or ring portion of metal 23 10 sufficiently large to nearly surround the boom with as much of the sail when wound upon it as will ever occur in actual practice. The ends of the ring part are arranged close together, but sufficiently removed to permit 15 the sail to pass between them. The corners are preferably rounded so as not to injure the cloth, and for the same reason they may be covered with leather or canvas, which will also prevent staining the sail. The boom-traveler 20 also comprises the part 24, which may be welded or otherwise firmly secured to the ring 23, but which, however, need not extend as completely around the boom as the ring 23. The part 24 is for the purpose of 25 supporting the sheet-block and permit it to pull at an angle without forcing one of the ends on the part 23 against the sail, the block sliding upon the part 24 to the proper position. The ends of the part 23 are provided 30 with upward extended portions 25, arranged on each side of the sail and having rounded extremities. These upwardly - extending portions or fingers are for the purpose of preventing the ring 23 from being rolled up with 35 the sail by the free end of the ring catching under the sail when the boom is turned.

The boom-swivel 26 comprises a plate secured to a bolt or other support 27, which may be screwed into the outer end of the 40 boom. A band 28 may be employed to prevent the latter from splitting. The boom-swivel is provided with an eye 29 for attachment to the topping-lift 30 and an eye 31 at the bottom for attachment of the free end of 45 the sheet 32. Below its point of suspension the swivel is provided with an enlarged portion 33, forming a weight and for the purpose of preventing the swivel turning with the boom. A cord or rod 34 connects the boom-swivel 50 and the boom-traveler and prevents the latter from moving along the boom in the direction of pull of the sheet.

The operation is as follows: In order to reef, the handle 15 is manipulated, causing 55 the pawl 16 to engage with the ratchet 14 and rotate the latter. The handle may be reciprocated, the boom being prevented from turning in the reverse direction by means of the pawl 18. As the boom is rotated the sail 60 will be wound up upon it, causing the jaw portion 8 of the boom-fitting to slide up the mast. The connections of the luff of the sail with the hoops can be cast off as the boom is

raised and the sail may be reduced any desired extent. Reverse rotation of the boom 65 will be prevented by the pawl 18. The entire sail, with the boom, may be now lowered by slackening away the halyards until the boom is in the desired position. The roller 19 will prevent jamming of the jaws 8 upon the mast, which would otherwise occur owing to the tendency of the boom to twist, as the sail is entirely upon one side of it. In order to shake out the reefs, the sail and boom are first hoisted up the mast. The pawl 18 is 70 then disconnected from engagement with the ratchet 14 and the boom permitted to turn to unwind the sail by disconnecting the pawl 16. In reefing or shaking out reefs the boom-traveler would have a tendency to wind up 75 with the sail were it not for the extensions 25. Similarly, the boom-swivel would turn and the gear become fouled unless a strain were kept upon the sheet. With a strain upon the sheet the difficulty of reefing would be greatly 80 increased, as the force required to roll the boom would have to be greater. With the extensions 25 on the boom-traveler and the weight 33 on the boom-swivel the sheet may be kept slack while reefing or shaking out 85 reefs and the operation rendered much more 90 easy and expeditious without danger of the gear getting fouled.

While the invention is described and illustrated as applied to a single fore-and-aft sail, 95 it is to be understood that it may be applied to any kind or number of sails as desired.

Having now described my invention, what I claim as new, and desire to secure by Letters Patent, is—

1. In a device of the character described, the combination with the boom, of a fitting engaging with one end of the boom, the said fitting having a socket, and a block engaging with a notch formed in the end of the boom. 100 105

2. In a device of the character described, the combination with the sail and the boom, of a boom-swivel on the free end of the boom, the said swivel having an attachment for the sheet, and a weight to prevent rotation of the 110 swivel.

3. In a device of the character described, the combination with the sail and the boom, of a boom-swivel on the free end of the boom, connections with the sheet, a weight below 115 the point of suspension of the swivel, a boom-traveler intermediate the ends of the boom, the said traveler surrounding the boom, and having extensions or fingers on each side of the sail and supporting a sheet-block, and 120 connections between the boom-swivel and boom-traveler to hold the latter in position.

4. In a reefing-gear, the combination with means for rolling the sail upon the boom, a jaw-fitting engaging with the mast, and a 125 roller within the jaw and engaging with the

mast, and a boom-traveler for the sheet, the said boom-traveler having a ring portion which nearly surrounds the boom, and having extensions or fingers at the free ends on each side of the sail, to prevent the free ends of the ring from being caught between the folds of the sail.

This specification signed and witnessed this 6th day of September, 1905.

MAX TORNOW.
